SWIM CAP

Adolph Reinsberg, Los Angeles County, Calif.,
assignor to Roger A. Marrs

Filed Oct. 24, 1965, Ser. No. 87,923

Term of patent 14 years

(Cl. D2—236)

FIG. 1 is a front perspective view of a swim cap showing my new design, the broken line showing of the head of a wearer is for purposes of illustration only;

FIG. 2 is a side elevational view of the swim cap shown in FIG. 1;

FIG. 3 is a front elevational view thereof; and

FIG. 4 is a top plan view.

I claim:

The ornamental design for a swim cap, substantially as shown and described.
